CASCODE MULTIVIBRATOR

Richard L. Ropiequet, Portland, Oreg., assignor to Tektronix, Inc., Portland, Oreg., a corporation of Oregon

Application August 18, 1953, Serial No. 374,959

16 Claims. (Cl. 250—27)

This invention relates to trigger circuits of the multivibrator type, and relates particularly to the novel construction of a multivibrator circuit which affords greater band width of operation and faster transition time than provided heretofore.

It is the principal object of this invention to provide a multivibrator which utilizes triodes in cascode and affords triggering at higher frequencies than provided heretofore.

Another important object of the present invention is to provide a multivibrator circuit in which the transition time is shortened substantially, whereby to reduce the operating time cycle.

A further important object of this invention is the provision of a multivibrator circuit which utilizes two pairs of triodes each arranged in cascode for bistable operation.

A still further important object of this invention is the provision of a multivibrator having a very precise level of triggering potential.

These and other objects and advantages of the present invention will be apparent from the following detailed description taken in connection with the accompanying drawing in which;

Figure 1 is a schematic diagram of a preferred form of multivibrator circuit embodying the features of the present invention;

Figure 2 is a schematic diagram of a modified form of multivibrator circuit embodying features of the present invention; and

Figure 3 is a schematic diagram of a still further modified form of multivibrator circuit embodying features of this invention.

In its broad aspect, the multivibrator of the present invention involves the arrangement of a pair of triode elements wherein the plate of one triode and the cathode of the other triode are connected together and the trigger signal is direct coupled to said connection.

The multivibrator shown in Figure 1 comprises four triodes V1, V2, V3 and V4. The plate 10 and cathode 11 of tubes V1 and V2, respectively, are connected together, as are the plate 12 and cathode 13 of the respective tubes V4 and V3. The cathodes 14 and 15 of tubes V1 and V4 are grounded, and the plates 16 and 17 of the tubes V2 and V3, respectively, are connected through the respective resistances 18 and 19 to a positive potential, for example +225 volts, as shown. The grids 20 and 21 of the respective tubes V2 and V3 are connected to a positive potential of, for example, 100 volts.

The grid 22 of tube V1 is connected through resistance 23 to a negative potential of, for example, -150 volts and is also connected through the parallel combination of resistance 24 and capacitor 25 to the plate 17 of tube V3.

In similar manner, the grid 26 of tube V4 is connected through resistance 27 to the negative potential and also through the parallel combination of resistance 28 and capacitor 29 to the plate 16 of tube V2. In this latter instance, however, it is preferred that the cathode follower tube V5 be used to couple the grid 26 of V4 and

2

the plate 16 of V2, for purposes to be explained in detail hereinafter. As shown in the drawing, the cathode 30 of tube V5 is connected in the circuit adjacent the resistance 28, and the grid 31 of said tube is connected through resistance 32 to the plate 16 of tube V2. The plate 33 of the cathode follower tube V5 is connected to a positive potential, for example 350 volts, as shown.

A particular feature of the present invention resides in the direct coupling of a positive trigger pulse 34, employed to trigger the multivibrator, at the junction 35 of the cathode 11 of V2 and the plate 10 of V1. Cathode follower tube V6 is employed for this purpose. The cathode 36 of tube V6 is connected to the junction 35, the grid 37 of this tube is connected to terminal 38 for receiving the trigger pulse, and the plate 39 is connected to a positive potential, as shown.

In similar manner, cathode follower tube V7 is employed to connect a trigger or reverting pulse to the right side of the multivibrator at junction 40 between the cathode 13 and the plate 12 of the respective tubes V3 and V4. The cathode 41 of tube V7 is connected to said junction 40, the plate 42 is connected to a positive potential and the grid 43 is connected to terminal 44, at which is applied the triggering or reverting pulse.

The operation of the multivibrator described hereinbefore is as follows: The left hand side (V1 and V2) of the multivibrator is normally conducting. A positive trigger pulse 34 applied to the grid 37 of the cathode follower V6 causes the latter to divert current from tube V2 so that the plate 16 rises in potential. The resulting positive step at this plate is coupled through cathode follower V5 to the grid 26 of the opposite lower tube V4. Thus, the multivibrator flops over, with conduction on the right side.

Cathode follower V5 functions as a buffer between the plate 16 of V2 and all other external loads. Thus, the only additional capacitance presented is the input capacitance of the cathode follower itself. The plate 16 of V2 is thus permitted to rise in potential at a much higher rate of speed than otherwise afforded.

The multivibrator described hereinbefore may be utilized for many purposes, such as in electronic counters and other instruments wherein trigger circuits are employed. It is particularly adapted for use in the cathode-ray oscilloscope for production of the time base. For such purpose the plate 17 of V3 is connected by terminal 45 to a sawtooth time base generator (not shown). The negative-going waveform provided at the right side of the multivibrator activates the sawtooth generator. It is convenient to couple the sawtooth generator back to the multivibrator junction 40 through cathode follower V7, by connection to terminal 44, so that the sawtooth sweep voltage itself may function upon reaching a desired level of potential to raise the potential of the grid 43 of the cathode follower V7 to a value at which this tube will divert current from the upper right tube V3 of the multivibrator and thereby effect reversion of the multivibrator to its initial stage, i. e. with the left hand side conducting.

A particular advantage of the multivibrator circuit described hereinbefore resides in the manner in which the trigger signal is introduced to the multivibrator. The points of injection 35 and 40 for the left and right sides, respectively, present a very low impedance when the corresponding side of the multivibrator is conducting. Accordingly, these points have very wide band width and thereby provide for the use of trigger signals of much higher frequency than heretofore permitted.

A further important advantage of the multivibrator circuit described hereinbefore resides in the use of cathode followers for introducing the trigger or reverting sig-

nal at the points 35 and 40, respectively. Since the cathode follower is characteristically of wide band width, the trigger signal is not only introduced at the most efficient point but also the total response of the multivibrator is greatly improved since the other points in the multivibrator are not loaded down with the trigger signal.

It will be apparent from the foregoing that the multivibrator illustrated in Figure 1 is stable in both directions, i. e. a trigger signal is required to be impressed at junction 35 to cause the multivibrator to flop over and a trigger signal is also required to be impressed at junction 40 to cause the multivibrator to revert to its initial state. The advantages of the present invention may also be realized with various other types of multivibrator circuits, for example the monostable circuits illustrated in Figures 2 and 3.

In Figure 2 of the drawing the multivibrator is shown to comprise the two pairs of triodes V1, V2 and V3, V4 arranged in the cascode configuration of Figure 1, with the exception that the grid 22 of tube V1 and the plate 17 of tube V3 are coupled together by means of capacitor 50 and grid 22 is also connected to a positive potential through resistance 51. The capacitor 50 and resistance 51 form an RC network which determines the time cycle of operation of the multivibrator and therefore the reverting signal coupled to junction 40 in the modification of Figure 1 is not required.

In the modification illustrated in Figure 3 of the drawing, the pentode tube V8 is substituted for the cascode arrangement of tubes V3 and V4 utilized in the multivibrator circuits illustrated in Figures 1 and 2. The cathode 60 is connected to ground and the screen grid 61 is connected to a positive potential. The suppressor grid 62 is provided with terminal 63 by means of which a negative signal 64 may be introduced to the right hand side of the multivibrator for purposes of reverting the latter. The plate 65 is connected through the parallel combination of resistance 66 and capacitor 67 to the grid 22 of tube V1, while the control grid 68 is connected through the parallel combination of resistance 69 and capacitor 70 to the plate 16 of tube V2. The grid 22 of tube V1 is connected through resistance 71 to a negative potential and grid 68 of tube V8 is connected through resistance 72 to a negative potential, in the manner of the modification shown in Figure 1.

It will be noted that in both of the modifications shown in Figures 2 and 3, the trigger signal 34 is impressed upon the multivibrator at the cascode junction 35, in the manner of the modification shown in Figure 1. Thus the modifications are each provided with a trigger injection point at very wide band width, as explained hereinbefore. Although the modifications of Figures 2 and 3 are illustrated in simplest form, it will be understood that various changes may be made therein. For example the cathode follower V5 shown in Figure 1 may be utilized in the plate circuit 16 of tubes V2 in the modifications of Figures 2 and 3 to provide the advantages of operation described hereinbefore. Further, the circuit arrangement of Figure 3 may be modified to provide the RC network of Figure 2, in manner well-known to those skilled in the art.

It will be apparent to those skilled in the art that various other changes in details of construction of the multivibrator circuit of the present invention may also be made without departing from the scope and spirit of this invention. Accordingly, it is to be understood that the foregoing description is merely illustrative of the invention and is not to be considered in a limiting sense.

Having now described my invention and the manner in which the same may be used, what I claim as new and desire to secure by Letters Patent is:

1. A trigger-actuated multivibrator comprising a plurality of electron discharge devices arranged in a normally conducting side and a normally non-conducting side, each

electron discharge device having cathode, grid and plate elements, one side of the multivibrator comprising a pair of electron discharge devices, the cathode of one electron discharge device of the pair being connected to the plate of the other electron discharge device of the pair, means connecting the plate of the said one electron discharge device of the pair and the grid of the said other electron discharge device of the pair to the other side of the multivibrator, the remaining elements of each electron discharge device being connected to a source of operating potential, and signal conductor means connecting a triggering signal to the said cathode-plate connection.

2. A trigger-actuated multivibrator comprising a plurality of electron discharge devices arranged in a normally conducting side and a normally non-conducting side, each electron discharge device having cathode, grid and plate elements, one side of the multivibrator comprising a pair of electron discharge devices, the cathode of one electron discharge device of the pair being connected to the plate of the other electron discharge device of the pair, means connecting the plate of the said one electron discharge device of the pair and the grid of the said other electron discharge device of the pair to the other side of the multivibrator, the remaining elements of each electron discharge device being connected to a source of operating potential, and cathode follower means connecting a triggering signal to the said cathode-plate connection.

3. A trigger-actuated multivibrator comprising a plurality of electron discharge devices arranged in a normally conducting side and a normally non-conducting side, each electron discharge device having cathode, grid and plate elements, one side of the multivibrator comprising a pair of electron discharge devices, the cathode of one electron discharge device of the pair being connected to the plate of the other electron discharge device of the pair, cathode follower means connecting the plate of the said one electron discharge device of the pair to a grid of the other side of the multivibrator, means connecting the grid of said other electron discharge device of the pair to a plate of the other side of the multivibrator, the remaining elements of each electron discharge device being connected to a source of operating potential, and cathode follower means connecting a triggering signal to the said cathode-plate connection.

4. A trigger-actuated multivibrator comprising a plurality of electron discharge devices arranged in a normally conducting side and a normally non-conducting side, each electron discharge device having cathode, grid and plate elements, the normally conducting side of the multivibrator comprising a pair of electron discharge devices, the cathode of one electron discharge device of the pair being connected to the plate of the other electron discharge device of the pair, means connecting the plate of the said one electron discharge device of the pair and the grid of the said other electron discharge device of the pair to the grid and plate, respectively, of the normally non-conducting side of the multivibrator, the remaining elements of each electron discharge device being connected to a source of operating potential, and signal conductor means connecting a triggering signal to the said cathode-plate connection.

5. A trigger-actuated multivibrator comprising a plurality of electron discharge devices arranged in a normally conducting side and a normally non-conducting side, each electron discharge device having cathode, grid and plate elements, the normally conducting side of the multivibrator comprising a pair of electron discharge devices, the cathode of one electron discharge device of the pair being connected to the plate of the other electron discharge device of the pair, means connecting the plate of the said one electron discharge device of the pair and the grid of the said other electron discharge device of the pair to the grid and plate, respectively, of the normally

a different electron discharge device of the other pair, cathode follower means in the connection between the grid of the normally non-conducting pair of electron discharge devices and the plate of the normally conducting pair of electron discharge devices, the remaining elements of each electron discharge device being connected to a source of operating potential, and cathode follower means for introducing a triggering signal to the cathode-plate connection of the normally conducting pair of electron discharge devices.

16. A trigger-actuated multivibrator comprising two pairs of electron discharge devices each having a cathode, a grid and a plate, the cathode of one electron discharge device of each pair being connected to the plate of the other electron discharge device of each pair, one pair being normally conducting and the other pair being normally non-conducting, the grid of one electron discharge device of one pair being connected to the plate of a different electron discharge device of the other pair, cathode follower means in the connection between the grid of the 20

normally non-conducting pair of the electron discharge devices and the plate of the normally conducting pair of electron discharge devices, cathode follower means for introducing a triggering signal to the cathode-plate connection of at least one pair of electron discharge devices, resistance means connecting the grids of the electron discharge devices having plate-connected grids to a negative potential, means connecting the cathodes of the electron discharge devices having plate-connected grids to ground, 10 and means connecting the plate and grid of each of the remaining electron discharge devices to positive potentials.
